UNITED STATES PATENT OFFICE.

JAMES M. THOMPSON, OF MONESSEN, PENNSYLVANIA.

LOCK-NUT.

1,159,131.

Specification of Letters Patent.

Patented Nov. 2, 1915.

Application filed July 17, 1914. Serial No. 851,589.

To all whom it may concern:

Be it known that I, JAMES M. THOMPSON, a citizen of the United States, residing at Monessen, in the county of Westmoreland and State of Pennsylvania, have invented 5 new and useful Improvements in Lock-Nuts, of which the following is a specification.

The present invention relates to improvements in means for effectively locking a nut upon a bolt to prevent the accidental dis- 10 association of the said nut and bolt.

In carrying out my invention I propose to provide a lock of this character which shall be of simple construction, cheap to 15 manufacture, easily and quickly applied and which shall be thoroughly efficient.

With the above and other objects in view, the invention resides in the construction, combination and operative arrangement of 20 parts set forth in the following specification and falling within the scope of the appended claims.

The drawings illustrate a simple and satisfactory reduction of the improvement to 25 practice, and in the said drawings,

Figure 1 is a transverse sectional view through a rail provided with fish plates and illustrating the application of my improvement to the connecting bolt, Fig. 2 is a front elevation of a plate employed with my device, Fig. 3 is a rear elevation of the same, Fig. 4 is a rear elevation of the spring member or washer, Fig. 5 is a front elevation of the same, and Fig. 6 is an elevation looking 30 toward the rear face of the nut.

While I have illustrated my improvement in connection with a rail joint, it is to be understood that the same is not to be thus limited in its useful application, as the improvement may be applied with equal efficiency upon all structures wherein it is desirable or essential that the connecting nut and bolt be retained locked against accidental separation from vibration or from 35 any other cause.

Referring now to the drawing in detail, the numeral 1 designates a rail of the ordinary construction, 2—2 the fish plates which engage with the opposite sides of the rail, 40 3 the bolt which passes through suitable openings in the fish plates and in the web of the rail, and 4 the nut for the bolt. In the present instance the fish plates 2 are channelled upon both their inner and outer 45 faces, and the head of the bolt 3 is of a width to engage with the beads formed by

the channel upon the outer face of one of the fish plates 2.

The numeral 5 designates a substantially rectangular plate which is constructed of 60 some spring material and which has its edges, upon its inner face, beveled or inclined, as indicated by the numeral 6, the said beveled edges contacting with the angular opposite faces of the beads formed 65 upon the outer face of the second fish plate. The plate 5 has its inner face dished or depressed, as indicated by the numeral 7; and if desired, and as illustrated in the drawing, the angular or beveled portion 6 may 70 be provided upon only two of the opposite edges of the plate. The plate is provided with a bolt opening 8 through which the shank of the bolt 3 passes, and the outer face of the plate is formed with depressions 75 or pockets 9, preferably two in number arranged diametrically opposite each other. By dishing or depressing the inner face of the plate 5, the central portion thereof is rendered yieldable for a reason which will 80 presently be described.

The numeral 10 designates a spring ring or washer member, the same having its inner face formed with lugs 11 which are adapted to be received within the pockets 9, and the 85 outer face of the said member 10 is formed with teeth 12 which radiate from the center of the said member.

The nut 4 is of any ordinary construction, but has its inner face provided with teeth 90 14 which radiate from the center thereof, and which are preferably arranged concentric of the bore of the said nut. When the nut 4 is screwed upon the threaded shank 95 of the bolt 3, after the members 5 and 10 have been associated, as above described, the teeth 14 of the nut 13 will ratchet over the teeth 12 of the spring member 10. The angular or beveled ends or edges 6 of the plate 5 will be forced tightly against the 100 opposite angular walls provided by the beads of the fish plate 2, causing the central portion of the plate to bulge outwardly, which movement forces the spring member or washer 10 toward the nut effecting a binding action between the teeth of the member 10 and the teeth of the nut.

What is claimed is:

1. The combination with a spring plate having opposite angular edges and its inner face depressed between the said angular edges, a bolt passing through an opening in 110

the plate, the outer face of the plate being formed with depressions, a spring member having a bolt opening and one of its faces provided with lugs which engage in the depressions of the plate, the outer face of the said spring member having teeth which radiate from its center, a nut for the bolt, and said nut having its inner face formed with teeth which engage with the teeth of the spring member when the nut is screwed home upon the bolt.

2. The combination with rails, of a fish plate for the rails, said fish plate having its outer face depressed to provide beads, the opposite sides of which are inclined, and a bolt passing through openings in the rails and fish plate, of a spring plate having opposite angular edges which contact with the angular faces of the beads of the fish plate, the said spring plate having a bolt opening to receive the bolt and its inner face channeled between its angular edges, the outer face of the said spring plate being formed with depressions, a spring member having a bolt opening and its inner face provided with lugs which are received within the depressions of the plate, the outer face of the said spring member having teeth, a nut for the bolt, and said nut having its inner face

provided with teeth which ratchet over the teeth of the member and engage therewith when the nut is screwed home upon the bolt.

3. The combination with a plate having its upper and lower edges beveled longitudinally and a bolt passing through the plate, of a spring plate having its inner face depressed and its longitudinal edges beveled to engage with the beveled longitudinal edges of the first mentioned plate and being further provided with an opening through which the bolt passes, the said spring plate having spaced depressions which communicate with the bolt opening, a spring ring having its inner face formed with lugs which are received within the depressions of the spring plate, and its outer face provided with teeth which radiate from the center of said ring, and a nut engaging the bolt and having its inner face provided with radially disposed teeth which co-act with the teeth of said ring member.

In testimony whereof I affix my signature in presence of two witnesses.

JAMES M. THOMPSON.
